UNITED STATES PATENT OFFICE

160,485

MILK BOTTLE CAP

Jacob J. Detzel, Chicago, Ill., assignor to Kayware Corporation, Chicago, Ill., a corporation of Illinois

Application August 25, 1949, Serial No. 4,691

Term of patent 14 years

(Cl. D58—26)

To all whom it may concern:

Be it known that I, Jacob J. Detzel, a citizen of the United States, residing at Chicago, in the county of Cook and State of Illinois, have invented a new, original, and ornamental Design for a Milk Bottle Cap, of which the following is a specification, reference being made to the accompanying drawing, forming a part hereof.

In the drawing:

Fig. 1 is a perspective view of a milk bottle cap embodying the invention;

Fig. 2 is a side elevational view;

Fig. 3 is a top plan view; and

Fig. 4 is a transverse sectional view.

I claim:

The ornamental design for a milk bottle cap, substantially as shown.

JACOB J. DETZEL.
